AUTOMATIC FILM FEED MECHANISM

Filed Nov. 21, 1929

UNITED STATES PATENT OFFICE

WILHO A. KOSKEN, OF RICHMOND HILL, NEW YORK, ASSIGNOR TO WILHO A. KOSKEN,
INC., A CORPORATION OF NEW YORK

AUTOMATIC FILM FEED MECHANISM

Application filed November 21, 1929. Serial No. 408,717.

This invention relates to moving picture projecting machines and particularly to a film feed mechanism for automatically feeding a relatively short length of film, when broken, out of the ray path to prevent the igniting of said film; and the object of the invention is to provide a mechanism of the class and for the purpose specified with means for rendering said mechanism normally inoperative whereby in the event of a break in the film especially at a point adjacent the transmission of the light rays therethrough, said mechanism may be put into operation to withdraw or remove the film from the ray path; a further object being to provide a mechanism of the class specified which is operated by a current of air under predetermined pressure, the source of the air supply being produced by a blower or compressor in operative connection with the machine or the film actuating means of the machine, the control of the direction of the air current to said film operating mechanism being governed by a member normally supported in inoperative position by its engagement with the film, whereby when a break occurs in the film said member is moved into operative position; a still further object being to provide in conjunction with said film operating mechanism, means whereby an electric motor or other power source employed for operating the film and the several parts of the machine may be stopped after the film has been removed from the ray path; and with these and other objects in view, the invention consists in a mechanism of the class and for the purpose specified which is simple in construction, efficient in use and which is constructed as hereinafter described and claimed.

The invention shown, described herein includes matter forming the subject of companion applications Serial No. 408,716, filed November 21, 1929, and Serial No. 408,718, filed November 21, 1929, and is fully disclosed in the following specification of which the accompanying drawing forms a part, in which the separate parts of my improvement are designated by suitable reference characters in each of the views, and in which:—

Fig. 1 is a diagrammatic, sectional view of

a part of a moving picture projecting machine, showing my improved mechanism applied thereto.

Fig. 2 is a sectional plan view of part of the construction shown in Fig. 1. 55

Fig. 3 is a vertical sectional view partially on the line 3—3 of Fig. 1; and,

Fig. 4 is a partial section on the line 4—4 of Fig. 3.

The invention herein disclosed relates primarily to the automatic film feed mechanism disclosed in the companion application herein referred to and in combination therewith, the means for stopping the machine operation. In the accompanying drawing, I have diagrammatically illustrated only such parts of the machine in connection with which this mechanism operates, it being understood that my invention is not necessarily limited to any particular type of machine. 60 70

In carrying my invention into effect, I employ a power element for actuating my improved mechanism and in the present case I have utilized air as such an element. In Fig. 1 of the drawing, I have shown at 10 the fan of a blower or air compressor arranged in a suitable casing or housing 11 and the shaft 12 of said fan has a gear 13 which meshes with a corresponding gear 14 on a shaft 15 which is in operative connection with and driven from the electric motor or other power source employed in the machine. The air from the fan 10 under predetermined pressure is discharged through a passage 16 which is flared and contracted at one end as seen at 17, note Figs. 1 and 2, and is discharged into the apparatus through a discharge passage 18. 75 80 85

In operative connection with the electric motor or other power source is a gear 19 which meshes with a gear 20 on the shaft of which is a film drive sprocket 21 which feeds the film 22 around an idler 23 as well as around a sprocket 24 arranged on a shaft 25, said sprocket being rotated in this operation. 90 The sprocket 24 is disposed below and in spaced relation to the idler roller 23 so that a relatively straight vertical portion 22a of the film will travel in a transverse line across the path of the rays, indicated in dot and 100

dash line at 26, emanating from a suitable source of light. Arranged at one side of the film and supported in the casing of the machine is a rectangular frame 27, note Fig. 4; and on the opposite side of the film is a U-shaped friction plate 28 loosely supported in connection with the casing by a screw 29. A spring 30 is employed to exert slight pressure upon the film to maintain the vertical portion 22a thereof in substantially taut condition for purposes later set out.

As clearly seen in Figs. 2 and 3 of the drawing, the sprocket 24 consists of two members disposed at opposite side edges of the film so as to permit the transmission of the rays 26 onto the film between the separate sprocket parts. Secured to the shaft 25 at a point exposed to the discharge 17 or a nozzle port 31 adapted to register with said discharge, is a rotor or bucket wheel 32 and a similar wheel 33 having a similar exposure is freely rotatable on the shaft 25 and is provided outwardly of the casing with a gear or pinion 34 with which a rack rod 35 is adapted to operate, the rack portion of which is shown at 36, note Fig. 1 of the drawing.

The rod 35 is arranged to move vertically in a yoke-shaped portion 37 of the casing and coupled with the rod and insulated therefrom is a contact 38 which is adapted to be moved into engagement with a stationary contact 39 insulated from its support. When these contacts are brought into engagement, a circuit is adapted to be completed to actuate a device to stop the electric motor or to short circuit said electric motor to stop the machine. The particular manner of performing this operation on the completion of a circuit may be accomplished in many ways and forms no specific part of my invention.

Pivottally supported in the casing adjacent the shaft 25 as seen at 40 is a lever 41, one end of which carries an anti-frictional roller 42 adapted to bear upon the relatively taut vertical portion 22a of the film to support the other end 43 of said lever normally in the full line position shown in Fig. 1 of the drawing. This end portion functions as a valve or air deflector, and when in the full line position, 50 serves to direct the air discharge from the passage 16 through the reduced end 17 out of the discharge 18 and to close the communication with the nozzle discharge 31; whereas, when the lever 41 drops into the dotted line 55 position on the breaking of the film, communication between the reduced end 17 and discharge 18 is closed, and the air is deflected in the nozzle discharge 31 and onto the rotors 32 and 33 causing said rotors to be actuated 60 in an anti-clockwise direction, the result of which will cause a broken portion of the film, positioned between the sprockets 21 and 24 to be fed backwardly or reversely and removed from the path of the ray 26, thus preventing 65 the ignition of the film.

In the same operation, the rotation of the rotor 33 will feed the rod 35 upwardly and after all of the film has been removed from the ray path, the contact 38 will be brought into engagement with the contact 39 to stop the operation of the machine. In connection with the foregoing brief description of the operation, it will be apparent that the friction or tension plate 28 serves to maintain the vertical portion 22a of the film in a relatively taut state in order to support the lever 41, which constitutes a control member, in its full line position.

It will also be understood that during the successful operation of the machine, the sprocket 24 as well as the rotor 32 are being constantly rotated whereas the rotor 33 remains stationary. In the particular type of machine which is diagrammatically illustrated, the rays of light from a suitable source after passing through the film are directed to one reflecting surface or prism 44 and reflected onto another reflector or prism 45 from which said rays are projected through suitable projecting lenses onto a screen. As previously stated, however, it will be understood that my improved automatic film feed mechanism and stop mechanism, may be applied to machines of any kind or class, the structure of the mechanism being modified to suit the particular apparatus in connection with which it is employed.

Various changes in and modification of the construction herein shown and described may be made within the scope of the appended claims without departing from the spirit of my invention or sacrificing its advantages.

Having fully described my invention, what I claim as new and desire to secure by Letters Patent, is:

1. In a projecting machine of the class described, the combination with that section of the film through which the rays of light emanating from a source of supply are adapted to pass, of a reverse feed mechanism turned idly in the normal directional feed of the film and automatically put into operation in the event of a break in the film adjacent said section to remove the free severed end of the film from the ray path.

2. In a projecting machine of the class described, the combination with that section of the film through which the rays of light emanating from a source of supply are adapted to pass, of a film controlled member, a reverse feed mechanism turned idly in the normal directional feed of the film and automatically put into operation by said member in the event of a break in the film adjacent said section to remove the free severed end of the film from the ray path, said mechanism involving a pneumatically actuated member.

3. In a projecting machine of the class described, the combination with that section of the film through which the rays of light em-

anating from a source of supply are adapted to pass, of a film controlled member, a reverse feed mechanism turned idly in the normal directional feed of the film and automatically put into operation by said member in the event of a break in the film adjacent said section to remove the free severed end of the film from the ray path, said mechanism involving a pneumatically actuated member, and said controlled member cooperating with the film and normally supported thereby in position to prevent the transmission of air to said pneumatically actuated member.

4. In a projecting machine of the class described, the combination with that section of the film through which the rays of light emanating from a source of supply are adapted to pass, of a film controlled member, a reverse feed mechanism turned idly in the normal directional feed of the film and automatically put into operation by said member in the event of a break in the film adjacent said section to remove the free severed end of the film from the ray path, said mechanism involving a pneumatically actuated member, said controlled member cooperating with the film and normally supported thereby in position to prevent the transmission of air to said pneumatically actuated member, and pneumatically actuated means for stopping the operation of the machine when the film feed mechanism has functioned.

5. In a projecting machine, means for feeding a film through the machine and in a plane transversely with respect to the path of light rays emanating from a suitable source of illumination, a member arranged adjacent that part of the film through which the light rays pass and rotated idly by the film as it is fed through the machine, and means involving a film engaging element whereby in a break of the film adjacent that part thereof through which the rays of light pass, said element will be moved into position to permit said member to be rotated in a reverse direction to reversely feed the film and withdraw the same from the ray path.

6. In a projecting machine, means for feeding a film through the machine and in a plane transversely with respect to the path of light rays emanating from a suitable source of illumination, a member arranged adjacent that part of the film through which the light rays pass and rotated idly by the film as it is fed through the machine, and means whereby in a break of the film adjacent that part thereof through which the rays of light pass, said member will be rotated in a reverse direction to reversely feed the film and withdraw the same from the ray path, said last named means involving a control device normally supported in operative position by engagement with the film.

7. In a projecting machine, means for feeding a film through the machine and in a plane

transversely with respect to the path of light rays emanating from a suitable source of illumination, a member arranged adjacent that part of the film through which the light rays pass and rotated idly by the film as it is fed through the machine, means whereby in a break of the film adjacent that part thereof through which the rays of light pass, said member will be rotated in a reverse direction to reversely feed the film and withdraw the same from the ray path, said last named means involving a control device normally supported in operative position by engagement with the film, and means for rendering the film taut where said device cooperates therewith.

8. In a projecting machine, means for feeding a film through the machine and in a plane transversely with respect to the path of light rays emanating from a suitable source of illumination, a member arranged adjacent that part of the film through which the light rays pass and rotated idly by the film as it is fed through the machine, means whereby in a break of the film adjacent that part thereof through which the rays of light pass, said member will be rotated in a reverse direction to reversely feed the film and withdraw the same from the ray path, said last named means involving a control device normally supported in operative position by engagement with the film, and means for automatically stopping the machine when the broken end of the film has been removed from the ray path.

9. In a moving picture projecting machine, a film feed mechanism for feeding the film through the light ray path of the machine, means in operative connection with the power source of the machine for creating and transmitting air under pressure through a predetermined path, a control member adjacent that part of the film through which the light rays pass and supported by the film to normally direct the current of air in one direction, a reverse drive device arranged adjacent said member and operatively engaging the film, said device being rotated idly in the normal feed of the film through the machine, and means whereby in the event of a break in said film, said member will be moved into position to direct the current of air toward said device to put the same into operation to feed the broken portion of the film in a reverse direction.

10. In a moving picture projecting machine, a film feed mechanism for feeding the film through the light ray path of the machine, means in operative connection with the power source of the machine for creating and transmitting air under pressure through a predetermined path, a control member adjacent that part of the film through which the light rays pass and supported by the film to normally direct the current of air in one

- direction, a reverse drive device arranged adjacent said member and operatively engaging the film, said device being rotated idly in the normal feed of the film through the machine, means whereby in the event of a break in said film, said member will be moved into position to direct the current of air toward said device to put the same into operation to feed the broken portion of the film in a reverse direction, said device being arranged adjacent that part of the film through which the rays of light pass and said device involving a sprocket engaging the film, and a rotor operated by the current of air.
11. In a moving picture projecting machine, a film feed mechanism for feeding the film through the light ray path of the machine, means in operative connection with the power source of the machine for creating and transmitting air under pressure through a predetermined path, a control member adjacent that part of the film through which the light rays pass and supported by the film to normally direct the current of air in one direction, a reverse drive device arranged adjacent said member and operatively engaging the film, said device being rotated idly in the normal feed of the film through the machine, means whereby in the event of a break in said film, said member will be moved into position to direct the current of air toward said device to put the same into operation to feed the broken portion of the film in a reverse direction, said device being arranged adjacent that part of the film through which the rays of light pass and said device involving a sprocket engaging the film and a rotor operated by the current of air, and another rotor adjacent said first named rotor and independently operated by the current of air, and means in operative engagement with the second named rotor for automatically stopping the operation of the machine.
12. In moving picture projecting machines, the combination with the film feed mechanism of the machine and the film actuated thereby, of an automatically actuated device for feeding a portion of the film in a reverse direction, said device being positioned adjacent that part of the film through which the rays of light pass and idly turned by the film in the normal feed thereof, means controlled by engagement with the film for controlling the operation of said device.
13. In moving picture projecting machines, the combination with the film feed mechanism of the machine and the film actuated thereby, of an automatically actuated device for feeding a portion of the film in a reverse direction, said device being positioned adjacent that part of the film through which the rays of light pass and idly turned by the film in the normal feed thereof, means controlled by engagement with the film for controlling the operation of said device, and means in operative engagement with the power source of the machine for supplying air under pressure to actuate said reverse feed device.
14. In moving picture projecting machines, the combination with the film feed mechanism of the machine and the film actuated thereby, of an automatically actuated device for feeding a portion of the film in a reverse direction, said device being positioned adjacent that part of the film through which the rays of light pass and idly turned by the film in the normal feed thereof, means controlled by engagement with the film for controlling the operation of said device, means in operative engagement with the power source of the machine for supplying air under pressure to actuate said reverse feed device, and said feed device including means for stopping the machine operation when a predetermined length of film has been reversely fed through the machine.
15. In a projecting machine of the class described, the combination with that section of the film through which the rays of light emanating from a source of supply are adapted to pass, of a film controlled member, a reverse feed mechanism turned idly in the normal directional feed of the film and automatically put into operation by said member in the event of a break in the film adjacent said section to remove the free severed end of the film from the ray path, said mechanism involving a pneumatically actuated element, and said member controlling the air supply to said element.
16. In projecting machines of the class described, a film feed mechanism involving feed means and a member rotated in one direction by the film fed through the machine, and means involving a control element operably engaging the film whereby a break in the film at a point adjacent said member and element will cause said element to be moved into position to permit the reverse drive of said member, and cause the reverse feed of the broken end of the film.
17. In projecting machines of the class described, a film feed mechanism involving feed means and a member rotated in one direction by the film fed through the machine, means involving a control element operably engaging the film whereby a break in the film at a point adjacent said member and element will cause said element to be moved into position to permit the reverse drive of said member and cause the reverse feed of the broken end of the film, and said member comprising a rotor pneumatically actuated in said reverse drive.
- In testimony that I claim the foregoing as my invention I have signed my name this 15th day of November 1929.
